(57) CLAIM

I claim the ornamental design for a shoe with slanted collar, as shown and described.

DESCRIPTION

FIG. 1 is a right side view of a shoe with slanted collar showing my design;

FIG. 2 is a left side view of the shoe with slanted collar shown in FIG. 1;

FIG. 3 is a top view of the shoe with slanted collar shown in FIGS. 1-2; and,

FIG. 4 is a rear view of the shoe with slanted collar shown in FIGS. 1-3.

The surfaces of the shoe with slanted collar that are not shown in the drawings, or described in the specification, form no part of the claimed design.

Surfaces and features indicated by broken lines are for illustrative purposes only and form no part of the claimed design.
